United States Patent Office.

JAMES JOHN, OF CHICAGO, ILLINOIS.

Design No. 4,669, dated February 21, 1871.

DESIGN FOR STUCCO CENTER-PIECE.

The Schedule referred to in these Letters Patent and making part of the same.

To all whom it may concern:

Be it known that I, JAMES JOHN, of Chicago, in the county of Cook and State of Illinois, have invented a new and original Design for Stucco Center-Pieces; and I do hereby declare that the following is a full, clear, and exact description thereof, which will enable others skilled in the art to make and use the same, reference being had to the accompanying drawing forming part of this specification.

The photograph represents a face view of my new design for stucco center-pieces.

This invention relates to a new design for an ornamental stucco center-piece.

The same is composed of the following parts:

A central rosette, *a*, is affixed to an oval or circular shield, *b*, which is surrounded by an oval or circular beaded border, *c*.

Ornamental crockets, *d d*, are placed at proper intervals against and upon the outer part of the border *c*.

A rectangular border, *e*, grooved as shown, embraces the oval or circular border *c*, being in part, however, covered by the same.

The outer ends of the crockets *d* lie in an oval or circular molding, *f*, which concludes the central part of the stucco.

A cavetto, *g*, surrounds the molding *f*, and is in turn surrounded by an oval or circular wreath, *h*.

Around the same is placed a broad, molded border, *i*, containing a series of spear-points, *j j*, which are placed radially to the center of the stucco.

A diamond-shaped or rectangular border, *K*, surrounds the border *i* tangentially, and another rectangular border, *l*, is placed about *K*, so that the corners of *l* are midway between those of *K*, as shown.

To the corners of the molding *K* are applied tufts, *m m*, of ornamental foliage, while the corners of *l* are ornamented by rosettes, *n n*.

The mixtilinear triangles formed between the border *i* and the corners of *K* are filled with projecting or pendent portions, *o o*, as are those between the sides of *K* and the corners of *l*.

From the foregoing it will appear that the same feature of design is applicable to center-pieces of oval as well as to such of circular form.

I claim as my invention—

The design for a stucco center-piece, as shown.

JAMES JOHN.
